CLAIM

The ornamental design for a wireless camera, as shown and described.

DESCRIPTION

FIG. 1 is a rear perspective view of a wireless camera, according to one embodiment of our new design;

FIG. 2 is a top view thereof;

FIG. 3 is a bottom view thereof;

FIG. 4 is a right side view thereof;

FIG. 5 is a left side view thereof;

FIG. 6 is a front view thereof; and

FIG. 7 is a rear view thereof.

FIG. 8 is a front perspective view of a wireless camera, according to another embodiment of our new design;

FIG. 9 is a top view thereof;

FIG. 10 is a bottom view thereof;

FIG. 11 is a right side view thereof; and

FIG. 12 is a left side view thereof;

FIG. 13 is a front view thereof; and

FIG. 14 is a rear view thereof.

FIG. 15 is an exploded front perspective view thereof; and, FIG. 16 is an exploded rear perspective view thereof.

Broken lines are used to illustrate features of the wireless camera that form no part of the claimed design.

1 Claim, 10 Drawing Sheets
